UNITED STATES PATENT OFFICE.

JOHN H. SCHUSSLER, OF CHICAGO, ILLINOIS.

AUXILIARY TRACK FOR PRINTING-PRESSES.

1,373,454.

Specification of Letters Patent. Patented Apr. 5, 1921.

Application filed February 14, 1919. Serial No. 276,896.

To all whom it may concern:

Be it known that I, JOHN H. SCHUSSLER, a citizen of the United States, residing at Chicago, in the county of Cook and State 5 of Illinois, have invented certain new and useful Improvements in Auxiliary Tracks for Printing-Presses, of which the following is a specification.

My invention relates to auxiliary tracks 10 for printing presses and is adapted to be secured to the frame of a printing press adjacent the tracks on the sides of the frame and upon which the inking trucks run. One of the objects of my invention is the provision of an auxiliary track which can be applied to the Gordon type of platen printing presses in order that the inking rolls may be adjusted with respect to the surface of the forms over which the inking rolls 15 pass.

Another object of the invention is the provision of means whereby wear on the track and also on the roller trucks may be taken up so that proper adjustment of the inking 20 rolls may be had at all times. It is well known that different weather conditions affect the composition of the inking rollers, and that some method of adjustment is necessary in order to insure the type surface 25 being properly inked. Heretofore it has been the custom to use shims of cardboard of various thicknesses in order to properly adjust the inking rollers with respect to the type. By the use of my invention all of 30 this will be obviated and proper adjustment of the inking trucks or rolls can be had at all times.

Another object of my invention is the provision of an auxiliary track which can be 35 easily and securely adjusted to different positions and which is also capable of very minute adjustment.

Another and further object of my invention is the provision of an auxiliary track 40 which can be secured to a printing press which has been in operation to such an extent that the tracks are worn, or the trucks of the inking carriage are worn, so that by applying these auxiliary tracks to the 45 press the wear of the tracks and inking rolls will be taken up. It will be understood, of course, that the track upon which the wheels of the inking rollers run has been formed heretofore on one edge of the frame 50 members and is integral with the frame of the printing press.

My invention is further and better understood by reference to the accompanying drawings and in which—

Figure 1 is a side elevation of my improved invention showing one of the tracks applied to a printing press. 60

Fig. 2 is a front elevation of a printing press parts being in section.

Fig. 3 is a sectional detail showing the manner of securing the track to the printing press frame. 65

Fig. 4 is a detailed view showing the key used for securing adjustment of the tracks.

Fig. 5 is a view of the bearing which I 70 use to insure the proper adjustment of tracks.

Referring now specifically to the drawings and in which my reference characters refer to like parts throughout, a printing press 75 frame 9 is shown the edges 10, 10 of which form the usual tracks upon which the wheels 11, 11^a of the inking truck run. An inking disk 11 is mounted upon the press by means of a standard 12 in the usual manner. 80 An auxiliary track 13 is secured to the printing press frame by means of a pair of lug bolts 14 and 15 respectively, which pass through inclined slots or openings 16 and 17 respectively in said track, and through 85 a bearing member 18 which is inserted in each of the inclined slots 16 and 17. The bearing member 18 has a projection 19 on its inner face, the said projection being approximately the width of one of the slots 90 16 and has bearing surfaces 20 and 21 respectively, against which the edges of the slots 16 and 17 engage. The bearing member 18 may be made in two parts if so desired although I prefer to make it in one 95 piece. Approximately centrally located of the said track 13 is an inclined opening 22 upon the lower edge of which teeth 23 are formed. A recess 24 is bored or drilled in the frame 9 of the printing press and within 100 which the head portion 25 of a key 26 is inserted. A handle portion 27 is secured to the head portion 25 of the key 26 so that a leverage can be exerted upon the head portion 25, which has formed thereon cogs 105 or teeth 28, 28 which engage the teeth 23 formed upon the lower edge of the opening 22 in the track so that by rotating the head 25 by means of the handle 27 the track 13 can be adjusted to different positions, it 110 being understood that the lug bolts 14 and 15 are loosened until the proper adjustment

of the track is obtained, whereupon the lug bolts are tightened so as to hold the track securely in position. The bearing member 18 through which the lug bolts 14 and 15 pass is positioned so that the projection 19 is inserted within the slots 16 and 17 with the edges of the slots in contact with the bearing surfaces 20 and 21 of the washer, the purpose of the projections on the bearing member 18 being to hold the track securely in alignment so that as the track is moved both ends of the track will be moved the same distance, and the track will not turn or bind, or one end move faster than the other. It will be understood, of course, that these tracks are provided in pairs, one track being secured to each side of the frame of the printing press and are made alike except that they are made in rights and lefts as shown in Fig. 2, where a track 28 is shown in section secured to the printing press frame by means of lug bolts 29 and 30. This track is made like the track heretofore described and illustrated in Fig. 1 of the drawings, except adapted to be secured to the opposite side of the press, so that further description is deemed unnecessary.

It will be understood that in the equipment of the printing presses the roller trucks are wide enough so that the rollers carrying these trucks will extend over the edge of the track 10 and come in contact with the auxiliary tracks 13 and 28, so that the tracks can be applied to old presses whose tracks have become worn or the rollers carrying the inking trucks have become worn to such an extent that a proper inking of the form is not effected. The application of the tracks to an old press is easily accomplished by tapping holes in the frames for the lug bolts 14 and 15, so that the track can easily be secured thereto, and by drilling a hole in the frame such as 24 to enable the key, such as 26, to be inserted in the recess and the track moved to proper position when the lug bolts can be tightened so as to securely hold the track.

While I have described more or less precisely the details of construction, I do not wish to be understood as limiting myself thereto, as I contemplate changes in form and the proportion of parts and the substitution of equivalents as circumstances may suggest or render expedient without departing from the spirit or scope of my invention.

I claim:

1. In a printing press of the type specified, auxiliary tracks for the inking rolls adjustably mounted on the frame of the press and having slots toothed along one edge, said frame having openings in register with the said toothed slots to receive and position a key in coöperative relation

with the said toothed slots to adjust the tracks, and means for securing the tracks in the adjusted position.

2. In a printing press of the type specified, auxiliary tracks for the inking rolls adjustably mounted on the frame of the press and provided with slots, securing means extending through the slots and engaging the said frame to fix the position of the tracks when adjusted, and means mounted on the securing means and comprising retainer portions engaging the outer sides of the tracks and guide portions entering the said slots and having extended engagement with the edges thereof to direct the tracks and maintain them in proper position during adjustment thereof.

3. In a printing press of the type specified auxiliary tracks for the inking rolls adjustably mounted on the frame of the press and provided with a plurality of relatively inclined slots extending in parallel relation, an intermediate slot of each track being toothed along one edge and the said frame having an opening opposite each toothed slot to receive and position a key in coöperative relation with the toothed slot to adjust the track, and securing means passing through the other slots and engaging the frame to fix the position of the tracks when adjusted.

4. In a printing press of the type specified, auxiliary tracks for the inking rolls adjustably mounted on the frame of the press and provided with a plurality of relatively inclined slots extending in parallel relation, an intermediate slot of each track being toothed along an edge and the said frame having an opening opposite each toothed slot to receive and position a key in coöperative relation with the toothed slot to adjust the track, securing means passing through the other slots and engaging the frame to fix the position of the tracks when adjusted, and members mounted on the securing means and engaging the outer sides of the tracks and provided with projections extending into the slots and engaging the edges thereof to direct the tracks and maintain them in proper position during adjustment thereof.

5. In combination, a printing press, auxiliary tracks having inclined slots therein, bolts extending through some of said slots and into the said printing press, washers carried by said bolts and having shoulder portions thereon for sliding engagement with the walls of said slots whereby angular movement of the tracks is prevented and a tool adapted to fit into a recess in said printing press for moving said tracks to different adjusted positions.

Signed at Chicago, Illinois, this 3rd day of February, 1919.

JOHN H. SCHUSSLER.
